UNITED STATES PATENT OFFICE.

JOSEPH P. BAUMGARTNER, OF PHILADELPHIA, PENNSYLVANIA.

GARTER CLASP.

Application filed August 26, 1922. Serial No. 584,474.

To all whom it may concern:

Be it known that I, JOSEPH P. BAUMGARTNER, a citizen of the United States, residing at Philadelphia, in the county of Philadelphia and State of Pennsylvania, have invented a certain new and useful Garter Clasp, of which the following is a specification.

The purpose of my invention is to facilitate the manufacture and particularly the assemblage of the fastener.

A further purpose is to provide retaining means for a buttonhole member applicable generally to members of this character.

A further purpose is to provide a keeper for the clasp member to hold it in position upon the supporting strap and capable of being snapped into position and out of position.

Further purposes will appear in the specification and in the claims.

I have preferred to illustrate my invention by but one form, selecting a form which has proved to be highly practical, effective and quite inexpensive and which at the same time well illustrates the principles involved.

Figure 1 is a front elevation of a garter with the parts in unclasped position.

Figure 2 is a front elevation with the parts in clasped position and with a stocking in place.

Figure 3 is a section upon line 3—3 of Figure 2.

Figure 4 is a section upon line 4—4 of Figure 3.

Figure 5 is a section upon line 5—5 of Figure 3.

Figure 6 is a section upon line 6—6 of Figure 3.

Figures 7 and 8 are perspectives of the clasp member and keeper respectively.

In the drawings similar numerals indicate like parts.

I have preferred to illustrate my invention upon a corset garter, though the same form of clasp can evidently be used upon any other form of depending garters, such as a man's garter, intended to grip the fabric of a garment such as a stocking.

In such garters there is provided a depending strap member 10 which in the case of a corset garter carries an adjusting

buckle 11 and a double loop bar 12 upon whose lower loop 13 the clasp straps 14 and 15 are secured.

The clasp straps are ordinarily formed of double strap material turned upon itself at 16 and 17, having an unbroken section about the bar at 18 and having the two ends terminating at the under side of the bar at 19 where they are attached by stitching 20.

The inner strap carries a preferably transversely directed and outwardly projecting oval button 21 which is mounted upon a plate 22 located between the two thicknesses 65 of the strap fabric, the button passing through an opening in the front of the fabric. The button is notched at 23.

Though features of the button construction were invented by me it is not my intention to claim them in this application.

The clasp member comprises primarily a turnable button-hole member 24 having an oval aperture 25 which registers with the oval button and, in the open position has its long axis transverse to the length of the strap. It interlocks with the oval button and in the closed position of the fastener, the longer axis lies parallel to the strap. This clasp member carries operating 80 knobs 26.

As these parts are made of celluloid there has been difficulty in the past in fastening the button-hole member in position upon the preferably metal bearing plate 27, within 85 which and upon which the button hole member turns.

This bearing plate is best shown in Figure 5 and is held in place upon the outside of the outer strap by teeth 28 clinched after 90 penetrating both thicknesses of the fabric.

The button-hole member and bearing plate make stop and resilient latch engagement with one another at the clasped and at the open positions. At each end of the 90° arc 95 29, the inwardly projecting knob 30 of the button-hole member makes stop engagement with the bearing plate simultaneously with registry and resilient interfitting of the projection 31 upon the bearing plate into one or other of the sockets 32 and 33 within the bearing face of the button-hole member. The button-hole member is held resiliently 100 to the bearing plate by means of a celluloid

washer fastened to the tubular shank 34 of the button-hole member inside the outer strap.

In the past it has been difficult to fasten a celluloid washer in place and in the best form of the prior art known to me, such a washer has been secured to the outer circumference of a tubular shank by cementing it thereto upon the under side of the strap.

- 10 This prior form is defective in that it takes a relatively long time to make the cemented joints, in that the joints are frequently weak from inadequate cementing, and in that their permanent character prevents easy inspection of parts beneath the washer where poor other construction is suspected.

I remedy all these defects and at the same time secure the requisite stability and resilience to press the bearing plate and the button-hole member together by grooving the tubular shank 34 at 36 and snapping into the groove the resilient inward projections 37 of the washer 38. This washer is radially slotted as at 39 at intervals about its inner circumference to form these inwardly directed resilient fingers.

The hold between this washer and the tubular shank of the button-hole member has proved quite effective, is applicable generally to retaining members of this character, the parts can be put together in a fraction of a second and the washer may be easily and quickly removed and replaced for rapid inspection of parts beneath the washer.

In operation the fabric 40 of the stocking is held by locking it between the button and button-hole members, as seen in Figures 2 and 3.

40 I recognize that in view of my disclosure others skilled in the art will probably see modifications and changes by which they may obtain all or a part of the benefit of my invention without copying it and it is my desire to secure herein all such modifications as come within the reasonable spirit and scope of my claims.

Having thus described my invention what I claim as new and desire to secure by Letters Patent is:—

50 1. In a garter clasp, a turnable button-hole member having a projection about the button-hole opening and a circumferential groove upon the projection in combination with a washer having an interior diameter smaller than the projection adapted to fit into the groove and divided radially near the inner circumference to permit the inner part to yield laterally so as to pass over the end of the projection and subsequently to spring into the groove.

60 2. A detachable and turnable clasp member comprising a button-hole member having an opening therethrough of elongated cross section and a rearward projection

about the opening of circular cross section grooved about its circumference, in combination with a washer of smaller internal diameter than the projection and adapted to yield laterally so as to pass over the projection and to spring back to enter the groove.

3. In a garter clasp, a button-hole member having a turnable front portion and a cylindrical hollow rear portion grooved about the circumference at the rear, a rearwardly directed projection thereon, a bearing member adapted to cooperate with the projection to limit movement of the button-hole member, a fabric through which the cylindrical rear portion passes and an internally resilient snap fastener adapted to pass over the rear end of the cylindrical portion and to snap into the groove.

4. In a garter clasp, depending inner and outer straps, an outwardly projecting button fixed to the inner strap and having an undercut oval head, a bearing member fixed to the outer strap larger in internal diameter than and in registry with the button, a turnable button-hole member upon the bearing member having an oval hole adapted to fit over the oval head and to interlock therewith by turning upon its axis from the position of registry, a shank upon the button-hole member extending through the bearing member and outer strap, and circumferentially grooved at the inner side of the outer strap, and a detachable resilient washer having separate resilient inwardly-directed portions adapted to be sprung over the shank and snapped into the groove to detachably hold the button-hole member in place upon the bearing member.

5. In a garter clamp, depending inner and outer straps adapted to register with one another, an outwardly projecting button fixed to the inner strap and having an undercut oval head, a bearing member fixed to the outer strap and internally registering with and larger than the head, a turnable button-hole member upon the bearing member having an oval hole adapted to fit over the oval head and to interlock therewith by turning upon its axis from the position of registry, comprising a tubular shank circumferentially grooved at the inner side of the bearing and circumferentially flanged at the outer side thereof, a detachable celluloid washer having slots spaced around its inner circumference and sprung into the groove to detachably and resiliently hold the button-hole member axially in place upon the bearing member, and interfiting parts on the flange and bearing member in registry when the button-hole member is in open position and also when in clasped position.

6. In a garter clasp, depending inner and outer straps adapted to register with one

another, an outwardly projecting button fixed to the inner strap having an undercut oval head, a bearing member fixed to the outer strap and internally registering with 5 and larger than the head, a turnable button-hole member having an oval hole adapted to fit over the oval head and to interlock therewith by turning upon its axis from the position of registry, and comprising a tubular 10 shank circumferentially grooved near its inner end and circumferentially flanged at its outer end, a detachable celluloid washer

having slots spaced around its inner circumference and adapted to be sprung into the groove to detachably and resiliently hold 15 the button-hole member axially in place in the bearing member and longitudinally interfitting parts on the flange and bearing member in registry when the button-hole member is in open position and also when 20 it is in clasped position and to limit the movement of the button-hole member.

JOSEPH P. BAUMGARTNER.
